REFRIGERATING METHOD AND APPARATUS

Joseph Raymond, Baltimore County, Md., assignor, by mesne assignments, to T. Calvin Baggett, H. Hamilton Hackney, George Myer, Joseph Raymond, and Robert I. Welsh

Application August 31, 1934, Serial No. 742,302

14 Claims. (Cl. 62—91.5)

The present invention relates to a refrigerating method and apparatus which utilizes as a refrigerant, solidified carbon dioxide, popularly known as "dry ice".

5 When solidified CO₂ is exposed to relatively elevated temperatures, instead of passing through a liquid state, it flashes directly into a gas, this phenomenon being known as sublimation. Such behavior is not restricted to atmospheric pressure, but is experienced at very high pressures as well. Thus when a mass of solidified CO₂, 10 optionally in the form of a compacted snow, is placed into a closed container and allowed to absorb heat, it will be transformed to a gas 15 with a resultant rise in pressure, and for all practical purposes, it may be said that the increased pressure will not appreciably impede evaporation.

Another peculiar property of the solidified CO₂ 20 is its action when immersed in a body of liquid. Although the dry ice has a low temperature and the liquid a relatively high one, evaporation of the dry ice will bring about little, if any, reduction of the temperature of the liquid. This 25 may possibly be explained by the poor conductivity of CO₂ gas, which, forming a layer of separation between the solid CO₂ and the liquid, prevents the transference of heat. Whatever the explanation, the fact remains, and it is to be 30 clearly understood that the present invention is not to be restricted to any theory, its practical operation being the basis of protection sought.

Whereas the pressure generated by evaporation 35 of a refrigerant has been utilized in a prior refrigerating system, exemplified by the patent to G. E. Hulse, 1,943,971, granted January 16, 1934, applicant is not aware of a system wherein dry ice is brought into direct contact with a liquid for causing evaporation of the refrigerant, 40 nor a system combining these two effects.

While there are many patents disclosing dry ice as a refrigerant, none of them has described a system of controlling evaporation whereby the cooling effects are economized. Some of the prior 45 systems permit constant evaporation of the refrigerant regardless of cooling demands, using only a small portion of the cooling effect. Such systems are wasteful on the one hand, and not susceptible to close regulation on the other.

50 The use of water-ice for cooling requires a large refrigerant compartment as compared with the size of the compartment to be cooled. Water-ice, moreover, passes to the liquid state and no utilizable pressure is developed during its evaporation.

Mechanical systems of refrigeration are not suitable for many types of installations, and require more space for the same cooling requirements than does the present system.

The present invention is especially suited to 5 the cooling of railway cars, passenger as well as freight, busses, trucks, private vehicles and boats. It is also intended for the refrigeration of food compartments, rooms, offices, and the various other uses to which mechanical and ice 10 systems would otherwise find application.

It is the object of the present invention to provide a method and apparatus for refrigerating in an economical and well controlled manner, avoiding the faults and limitations inherent to 15 the prior art. By providing a relatively simple apparatus, the initial expense of installation is kept to a minimum, and by virtue of its efficient operation, there is realized a maximum saving 20 during the use of the apparatus.

In general, the apparatus comprises a closed container having conducting walls through which the heat may be directly or indirectly transmitted from the body which is ultimately to be cooled. Means is provided for supporting the body of 25 evaporative refrigerant, preferably above the bottom of the container, there being a compartment at the bottom for the reception of the liquid whose extent of contact with the refrigerant, controls the rate of evaporation of the latter. 30 The apparatus is equipped with adjustable means to vary the effective liquid level in accordance with pressure values within the container, which values are preferably those resulting from evaporation of the refrigerant. One or more adjustable 35 vents are provided for the container to prevent the production of dangerous pressures therein. A storage tank is also contemplated for collection of the CO₂ gases, which may be re-solidified or put to other uses, such as carbonating 40 liquids.

Mechanism is contemplated to maintain uniform pressure throughout the container and to insure against freezing of the operating parts. Besides the control in accordance with pressure, 45 auxiliary control is accomplished in accordance with the temperature conditions of any point under the influence of the system.

The system is made to operate intermittently with a frequency capable of variation according 50 to the rate of cooling required. Continuous operation is likewise possible, and the system is capable of wide flexibility, though close regulation.

Having stated some of the general character- 55

- istics of the apparatus, a more complete understanding will follow a study of the detailed structure described in conjunction with the drawing, in which:
- 5 Fig. 1 is a sectional elevation illustrating one form of the apparatus; and
- 10 Fig. 2 is a sectional elevation of a modified form, the adjusting mechanism for the liquid level not appearing in this view.
- 15 Referring to Fig. 1, a metallic container 10 is provided with a closure 11, shown as of the man-hole type commonly employed in boilers. A gasket 12 and fastening means 13 are provided for the closure, whereby a fluid tight joint is achieved.
- 20 As is usual with such a joint, the seal improves as the internal pressure increases.
- 25 Spaced from the bottom of the container 10 and suitably suspended from its vertical walls, there is a perforated refrigerant support 14 dividing the container into a refrigerant compartment 15 and a liquid compartment 16.
- 30 Communicating with the liquid compartment, there is a pipe 17 provided with branch pipes 18 and 19, joined by a T-fitting 20. Branch pipe 18 leads into the bottom of a pressure dome or tank 21, closed at its upper end. The branch pipe 19 leads to the upper portion of the container 10 for a purpose to be described.
- 35 A valve 22 is inserted in the pipe 17 and is adjusted, by means of a screw 23 or similar element, to open when it is subjected to a predetermined fluid pressure. Thus until the pressure in question assumes the predetermined value, the valve will remain closed. Pressures equal to or exceeding the preset value will cause the valve to open and remain open until the pressure again drops below that for which the setting has been made, whereupon the valve closes until a new elevated pressure reopens it. By adjustment of the screw, this predetermined value may vary over a wide range, and for all practical purposes, is limited only by the operating conditions of the system.
- 40 The tank 21 contains a body of air or gas 24 which will be compressed as the column of liquid 25 rises, and thus, will tend to stabilize the height of the liquid column. A valve 26 is provided at the closed end of the tank 21, by which additional liquid and/or gas may be introduced through the pipe 27 projecting therefrom.
- 45 Surrounding the container 10, there is a jacket 28 containing a pipe coil 29 having an inlet end 30 and an outlet end 31. The jacket is shown as provided with bimetallic elements 32 and 33 which close the jacket to the atmosphere when the temperature of fluid within the coil 29 is too high, but open when this temperature is reduced excessively, and thus prevent solidification of such fluid or undesirable cooling thereof.
- 50 Leading from the top of container 10, is a pipe 34 through which excess gases resulting from evaporation may be withdrawn. Tapped from pipe 34, there is a conduit 35 leading to a gas storage tank 36 from which CO₂ gas may be withdrawn through a pipe line 37 leading to a closed system diagrammatically shown at A, which may be a carbonator, compressor, or other apparatus utilizing such gas. Optionally, if no such system is contemplated, the pipe line 37 may be capped. A check valve 38 in the pipe 34 prevents gas in the storage tank 36 from reentering the container 10. A blow-off valve 39 on the storage tank may be set to any desired value of storage pressure. A valve 40 in the pipe 34 is

used to control the operation of the system as will appear hereinafter.

A thermostatic bulb 41, shown as in contact with the outlet 31 of the coil 29, operates a valve 42, also in the pipe 34. When the temperature 5 of the fluid in the coil 29 is too high, thermostatic fluid in the bulb 41 expands into its tube 43 causing the valve 42 to open and relieve pressure within the containers 10 by allowing gas from the latter to discharge to the atmosphere. 10

In the event that the valve 42 should fail for any reason, and the temperature within the coil 29 continue to increase, increased pressure within the container 10 will force liquid up through pipe 19 and its valve 44, adjusted by its adjusting 15 screw 45 to a yielding pressure somewhat in excess of the opening point of valve 22, and deliver such liquid over the body of solidified refrigerant 46 in the container, causing further evaporation thereof. 20

Should the dry ice or solidified refrigerant 46 freeze against the walls and divide the container into two compartments, liquid will be forced by the resultant pressure at the lower end, up through a tube 47 suitably mounted on the container wall, and cause sufficient evaporation of the refrigerant to again equalize pressures throughout the container and clear the walls thereof. 25

Upon the generation of pressures within the 30 container exceeding those which are safe or necessary for the operation of the system, a safety valve 48 provided in the closure will vent the container and reduce the pressure to a normal and safe value. In lieu of such a valve, a disk 35 may be employed which will become ruptured and require replacement.

In operation, if an operating pressure of 50 lbs. per square inch is desired, the valve 22 is set to this value by its adjusting screw 23. Assuming 40 that the desired storage pressure is 15 lbs. per square inch, the blow-off valve 39 is set to this value. Valve 44 will be set to open at some pressure slightly in excess of the setting of valve 22, and valve 48 set to blow off at a pressure assuring 45 safe operation.

The closure 11 will be removed from the container 10, and a charge of solidified CO₂ will be lowered to rest upon its support 14. The liquid level in the lower part of the container will be 50 above the perforated support, the actual height depending upon the amount of liquid in the system and the pressure of the fluid body 24. The liquid contacting the refrigerant 46 will cause the latter to start evaporating and upon bolting 55 the closure in fluid tight relation with the container, this evaporation will begin to build up a pressure within the container.

Evaporation continues as long as the liquid contacts the refrigerant. Thus until the container pressure reaches the setting of the valve 22, evaporation continues at an undiminished rate. As soon as the pressure reaches 50 lbs. per square inch, valve 22 opens and the gas pressure tends to force the liquid from the container into 65 the tank 21, compressing the fluid body 24. When contact between the liquid and refrigerant is broken, evaporation stops, and as long as the pressure within the container is sufficient to maintain this condition, there will be no further 70 evaporation. However, when the pressure reaches a value corresponding to the setting of valve 44, the latter will open and permit some of the liquid to flow over the refrigerant and set up some further evaporation. Should the pres- 75

sure continue to build up in this manner, safety valve 48 will ultimately open and vent the container to avoid dangerous consequences.

The actual operating cycle however, depends upon the adjustment of valve 40. When this valve is opened a small amount, the CO₂ gas will escape slowly, whereby there will be alternate periods of contact between the refrigerant and liquid, with relatively long periods of no such contact. A greater opening of the valve 40 causes the intermittent contacts to occur with greater frequency, with a correspondingly greater rate of evaporation. Increased opening of the valve increases the contact periods, until finally, continuous evaporation may be achieved by allowing the gas to escape as rapidly as it is generated. The escaping gas may be discharged to the atmosphere and wasted, or, it may be stored in a tank such as 36 from which it may be drawn off as needed for desired purposes.

If the valve 40 has not been opened sufficiently to cool the fluid in the coil 29 to a proper degree, thermostatic fluid in the bulb 41 will expand and vent the container by opening the valve 42, bringing about an increased evaporation and a corresponding increase in cooling effect.

With regard to the structure and operation set out above, it should be borne in mind that the structure considered is illustrative only and not restrictive. For example, in lieu of the tank 21 and valve 22 together with their appurtenances, the bottom of the container 10 could be formed of a flexible diaphragm for allowing the liquid to break its contact with the refrigerant in response to internal pressures. Such a diaphragm could be given an adjustable responding value by backing it with a spring of variable tension or a balance beam with a sliding weight. As a matter of fact, the apparatus as shown would be operative without the pipe 19 and its valve 44. The thermal control could well be accomplished electrically according to known methods of thermally controlling valves. The bulb 41 or other temperature sensitive device could be located at any point under the influence of the system instead of on the outlet end of the coil.

The apparatus is by no means confined to its use in conjunction with a coil. In Fig. 2 another use is depicted, namely, cooling a fluid body such as air or gas. The container 10 is in this instance surrounded by a duct 49, both of which will be suitably supported in a manner not shown since the drawings are diagrammatic to a large degree.

The duct may convey air or gas of any kind, with or without suspended solids, such as dusts employed for industrial purposes. The inlet opening 50 may be provided with a fan or blower 51 for circulating the fluid to be cooled. The co-extensive walls of the container 10 and the duct 49 are shown as carrying baffles or vanes 52 for exposing the flowing fluid to a maximum cooling surface, and for this purpose, the baffles carried by the duct may have metallic contact with the container wall.

A thermostatic bulb 53 is shown in the outlet end 54 of the duct 49, suitably supported thereby. As in the preceding case, when the temperature of the delivered fluid is too high, the fluid expansion within the bulb and its tube 55 opens a valve 56 and vents the container 10, bringing about an increased evaporation. This valve may discharge to the atmosphere or into the duct itself, as desired. The actual operating mechanism has not been shown in this figure, but it may assume any of the forms contemplated for

the preceding illustration. The gas discharged from the apparatus may be used to produce an injector or ejector action in the duct to promote increased circulation of the fluid to be cooled. For charging the container of Fig. 2 with refrigerant, a manhole 57 in the duct 49 has been indicated in dotted lines to show one operative means.

The thermostatically operated valves are preferably of an adjustable type, so that they may come into play at any desired temperature.

The liquid used to cause evaporation of the refrigerant will have such a low freezing point that the conduction by the container walls will not cause it to solidify.

The various valves may be immersed in a similar liquid if it is necessary to provide an assurance against their freezing.

The valve 22 will remain open as long as pressure on either side thereof exceeds the pressure for which it is set.

The claims should be construed to include a condition where the refrigerant itself assumes various levels and the body of liquid has a fixed height.

Where employed for cooling air, the apparatus may be combined with dehumidifying apparatus to prevent the formation of rime on the container and its baffles.

This invention is not to be limited to the specific embodiments shown since it covers a large number of alternatives, a few of which have been suggested. The scope of the invention is measured by the following claims:

1. A method of refrigerating comprising bringing a solid refrigerant and a relatively warm liquid into contact in a substantially closed container, progressively decreasing the mutual contact between said refrigerant and said liquid under operating conditions as the vapor pressure resulting from sublimation of the refrigerant increases above a predetermined value, and venting said container when the vapor pressure exceeds another predetermined value.

2. A method of refrigerating comprising placing a solid refrigerant into a substantially closed container in the presence of a body of liquid which directly contacts the refrigerant below a predetermined pressure in the container, under operating conditions causing the liquid to recede from contact with the refrigerant as the pressure within the container increases, and venting said container upon further increase of pressure beyond a predetermined value.

3. A method of refrigeration comprising placing a solid refrigerant into a substantially closed container in the presence of a body of liquid, causing the liquid to remain in contact with the refrigerant below a predetermined pressure, under operating conditions breaking the contact between the liquid and refrigerant when the pressure exceeds the predetermined value, and venting said container at a pressure exceeding a second predetermined value.

4. A method of refrigerating comprising placing a solid refrigerant into a substantially closed container in the presence of a body of liquid, causing the liquid to remain in contact with the refrigerant below a predetermined pressure, under operating conditions breaking the contact between the liquid and refrigerant when the pressure exceeds the predetermined value, and venting the container when the pressure exceeds a second predetermined value, the pressure values resulting from sublimation of the refrigerant.

5. A method of refrigerating comprising placing a solid refrigerant into a substantially closed container in the presence of a body of liquid, causing the liquid to contact the refrigerant at pressures within the container below a predetermined value, breaking the contact between the liquid and refrigerant at pressures within the container above the predetermined value, venting the container at pressures above a second predetermined value, and transferring heat through the container wall. 5
6. A method of refrigerating comprising placing a solid refrigerant into a substantially closed container in the presence of a body of liquid, causing the liquid to contact the refrigerant at pressures within the container below a predetermined value, breaking the contact between the liquid and refrigerant at pressures within the container above the predetermined value, and venting the container at pressures exceeding a second predetermined value. 10
7. A method of refrigerating comprising placing a body of dry ice into a substantially closed container in spaced relation with the bottom thereof, providing a body of liquid in the space below the dry ice under operating conditions varying the effective liquid level for intermittent and varying extent of direct contact with the dry ice in accordance with instantaneous pressures within the container and venting said container at a predetermined pressure. 20
8. A method of refrigerating comprising controlling the rate of evaporation of a refrigerant in a substantially closed container by directly contacting said refrigerant with a body of liquid whose effective level may be varied, varying the effective level of said liquid by the joint effects of pressure within the container and the temperature at a point under the influence of the system and venting said container at a predetermined pressure. 30
9. Refrigerating apparatus comprising a container having conductive walls, means supporting a body of evaporative refrigerant in direct contact with a body of liquid in said container, means responsive to pressure within the container for adjusting the extent of contact between said refrigerant and said liquid and means for venting said container at a pressure in excess of a predetermined value. 40
10. Refrigerating apparatus comprising a container having conductive walls, means supporting a body of evaporative refrigerant in direct contact with a body of liquid, means responsive to pressure within the container for adjusting the extent of contact between said refrigerant and said liquid, means responsive to temperature at a point under the influence of the apparatus for adjusting the extent of contact between said refrigerant and said liquid and means for venting said container at a pressure in excess of a predetermined value. 5
11. Refrigerating apparatus comprising a container having conductive walls, means supporting a body of evaporative refrigerant in direct contact with a body of liquid in said container, means responsive to pressure within the container for adjusting the extent of contact between said refrigerant and said liquid, means insuring uniform pressure throughout the container, and means for venting said container at a pressure in excess of a predetermined value. 15
12. Refrigerating apparatus comprising a container having conductive walls, means supporting a body of evaporative refrigerant above the bottom of said container, a liquid compartment in the bottom of said container, means automatically adjusting the liquid level in said compartment responsive to pressure within the container, means for varying the automatic adjusting means and means for venting the container at a pressure in excess of a predetermined value. 20
13. Refrigerating apparatus comprising a container having conductive walls, means supporting a body of evaporative refrigerant for direct contact with a body of liquid in said container, means for adjusting the rate of evaporation of said refrigerant under operating conditions, and means for venting said container at a pressure in excess of a predetermined value. 30
14. Refrigerating apparatus comprising a container having conductive walls, means supporting a body of evaporative refrigerant for direct contact with a body of liquid in said container, means for adjusting the rate of evaporation of said refrigerant, and means for venting said container at a pressure in excess of a predetermined value. 40
